UNITED STATES PATENT OFFICE

PETER J. SHRUM, OF MONACA HEIGHTS, PENNSYLVANIA, ASSIGNOR TO PITTSBURGH SCREW AND BOLT CORPORATION, A CORPORATION OF PENNSYLVANIA

THREAD PROTECTOR

Application filed November 8, 1927. Serial No. 231,842.

This invention relates to improvement in thread protectors.

In Patent No. 985,946, issued to me under date of March 7, 1911, discloses a thread 5 protector similar in construction to the present invention, but is unlike the present invention as will be readily understood as the specification progresses.

An object of this invention is to provide 10 a thread protector which is easily applied and which provides effective protection for threads as well as the shoulders of the tool or other device to which the protector is applied and in addition to affording such protection to form an effective seal about the threads.

Another object of this invention is to provide 20 a thread protector having the above characteristics and means associated therewith for lubricating the threads to be protected and preventing the access of water or other foreign matter thereto.

These and other objects are obtained by 25 means of the protector illustrated by the single sheet of drawings, in which,

Figure 1, is an end view of the protector embodying the invention,

Fig. 2, is a sectional view taken along the line II—III of Figure 1.

Fig. 3, is an elevational view of a thread 30 engaging flange embodying the invention,

Fig. 4, is a fragmental view of Figure 3, showing the lubricating pad or strip embodying the invention, and

Fig. 5, is an end view of Figure 3.

The thread engaging or ring-holding element 12 and the outer protecting ring 15 are substantially the same shape at the parts 3 and 6 described in my above mentioned 40 patent and operate the same in every respect.

In the drawings 11 is a threaded pipe or other threaded article to be protected having the usual spiral thread extending backwardly along its end, over which the protector is to be inserted sufficiently far to completely protect the threads.

The protector comprises a thread engaging or ring holding element 12, which may 50 be completely circular or of any desired cir-

cular continuity, but having separate ends as shown, so as to provide for resiliency and adjustment. The thread engaging element 12 is turned inwardly at one end providing a thread engaging flange 13, the function of which is to engage the thread when the ring is inserted over the article to be protected and operating to hold it fixedly in place. The ring 12 is provided with a number of locking or holding tongues 14 for engaging and cooperating with an outer protecting ring 15. The outer protecting ring 15 is cylindrical in shape and is provided with an outer, inwardly turned annular flange 16 which operates to protect and reinforce the end of the threaded pipe 11 and to cooperate with the locking tongues 14 on the thread engaging element 13. In addition to the thread engaging element 12 and the outer protecting ring 15, the present protector is provided with a suitable strip 17, such as felt which is adapted to carry a lubricant for lubricating the threads disposed on the end of the pipe 11. The strip 17 is positioned around the inner walls of the thread engaging element 12, so that when the protector is placed in position on the end of the pipe 11 the strip 17 lies between the thread engaging element 12 and the threads on the end of the pipe 11 to be protected. It can be seen from the above that when the outer protecting ring 15 is positioned on the thread engaging element 12 that the felt strip 17 is caused to be pressed firmly in contact with the threads to be protected.

The present protector ring 12 and thread engaging element 17 have diameters slightly larger than the corresponding diameters of the protecting ring and thread engaging element employed in my above mentioned patent for accommodating the lubricating pad between the thread engaging element and the threads to be protected, also the flange 13 of the present invention is slightly wider than the flange 4^a employed with my above mentioned protector.

The present thread protector prevents water, dust or the like from injuring the threads and positively seals the threads and

maintains them lubricated and in ready operable condition.

While I have illustrated and described this lubricating pad in connection with my above mentioned patent, it will be obvious that this pad may be adapted for use with other thread protectors by making such changes in the protector for which its use is desired to accommodate the lubricating pad.

10 Other changes, modifications, substitutions, additions and omissions may be made in the present protector without departing from the spirit and scope of the appended claims.

What I claim as new and desire to secure 15 Letters Patent on, is:

1. The combination of a thread protector comprising a plurality of concentric rings having a thread engaging flange on the inner ring thereof, of a lubricating pad disposed on the inner surface of the protector adjacent the said thread engaging flange.

2. A thread protector comprising an inner ring having a thread engaging element, an outer ring for receiving the inner ring, a 25 pad around the interior of the inner ring, and means for locking one of the said rings in fixed relation with the other.

3. A thread protector comprising an inner ring having a thread engaging flange, a 30 lubricant pad disposed on the inner surface of the inner ring, an outer ring adapted to compress said flange and lubricant pad into engagement with the threads and means forming an integral part of one of the rings 35 for locking it in fixed relation with the other ring.

4. A thread protector comprising an inner ring having a thread engaging flange and a locking tongue, an outer ring adapted to 40 embrace said inner ring and to be fixedly engaged by said locking tongue and a lubricant pad disposed on the inner surface of the inner ring.

5. The combination in a thread protector 45 of a lubricating pad, an inner ring adapted to embrace the said lubricating pad having a thread engaging flange and locking tongues and an outer ring adapted to embrace said inner ring and to be fixedly engaged by said tongues.

6. In combination in a thread protector, a yielding pad for engaging threads to be 50 protected, a resilient member surrounding said pad and having a thread engaging flange formed thereon, and a rigid sleeve encircling said member for holding said flange in thread engaging position.

7. In combination in a thread protector, a yielding pad adapted to engage threads to be 55 protected, a resilient member surrounding said pad and having a thread engaging flange at one end thereof and at least one locking tongue at the other end thereof, a rigid ring surrounding said member for 60 pressing said flange and said pad in thread

engaging position, and locked in place by said tongue.

In testimony whereof, I have hereunto subscribed my name this 26th day of October, 1927.

PETER J. SHRUM.
